THOMAS G. CLIFFORD, OF HOBOKEN, NEW JERSEY, ASSIGNOR TO GARRETT F. ROSE, OF NEW YORK, N. Y., AND THOMAS G. CLIFFORD, JR., OF HOBOKEN, NEW JERSEY.

TESTING-PLUG FOR PLUMBERS' USE.

SPECIFICATION forming part of Letters Patent No. 739,589, dated September 22, 1903.

Application filed February 25, 1903. Serial No. 144,963. (No model.)

To all whom it may concern:

Be it known that I, THOMAS G. CLIFFORD, a citizen of the United States, residing in Hoboken, in the county of Hudson, in the State of New Jersey, have invented a certain new and useful Improvement in Testing-Plugs for Plumbers' Use, of which the following is a specification.

It is common in the construction of the plumbing work in a building to complete the cast-iron portion which involves the main upright pipe and the several branches and before connecting the lead pipes, faucets, &c., to test the tightness of the cast-iron parts. This is done by subjecting the cast-iron parts to a pressure of condensed air induced by a suitable compressing-pump. All the openings, except that where the air is introduced, require to be plugged tightly for the time being. It is important to allow any one of the plugs selected at random or otherwise to be used for introducing the air to provide for making a tight joint around in the one where the pump is used and also for easily and completely freeing the openings again by the complete removal of the plugs when the test is completed.

I have devised a construction of testing-plug which is peculiarly simple, makes a tight joint at the end of the pipe, and reaches in a sufficient distance and takes hold reliably on the smooth interior of the pipe. I provide a sufficient length to reach down beyond the hub, so that it may be used on the ordinary ends where hubs are presented; but it may be also used with success on an end where there is no hub. The grip on the interior is obtained by a wedging action. The wedge acts on a short length of rubber tube, making available the highly frictional qualities of that material. The wedge may be drawn up by turning a thumb-nut running on a threaded surface of a small central tube, which tube serves as a rod to communicate the tension to the wedge-piece and also as a tube through which the air may be introduced when the testing apparatus is connected. The ends in the system other than the one through which the air is pumped are stopped by screw-caps. The releasing is effected by simply slacken-

ing the thumb-nut and driving down the tube, thus releasing the wedge, which should be made with so much taper as to let go easily.

The following is a description of what I consider the best means of carrying out the invention.

The accompanying drawings form a part of this specification.

Figure 1 is a general side elevation of the plug with a cross-section of the pipe in which it is applied. Fig. 2 is a central vertical section through a portion on a larger scale, the section being on the line 2 2 in Fig. 4. Fig. 3 is a corresponding section on the line 3 3 in Fig. 4. Fig. 4 is a cross-section on the line 4 4 in Fig. 3. Fig. 5 is a central vertical section showing a modification.

Similar letters of reference indicate corresponding parts in all the figures where they appear.

A is a pipe, and A' the hub on the end thereof. It may be understood to be the upper end of the main pipe, which extends vertically through the whole depth of the building; but all the parts would serve equally well, except that the device should be inclined if it were attached to an inclined branch, of which there is one or more at every floor.

B is a stout disk of wood or other suitable material adapted to bear considerable strain. b is a hole therein, and b' a rabbet around such hole.

C is a gasket of rubber applying under the whole lower face of the disk from the periphery inward to the rabbet. When the device is in use, this disk and gasket apply tightly and are held down forcibly on the smooth upper end of the hub A'.

D is a tube screw-threaded for a considerable length at each end and extending loosely up and down through the hole b. On its upper part is a sufficiently-stout washer E, above which applies a stout thumb-nut F. Between the washer E and the upper face of the disk B is a rubber washer G, which when compressed by the action on the nut makes a tight contact around the tube D. On the threaded lower part of this tube D are applied two nuts D' D'', and embraced between them is a piece M. It is a tapering partial plug, large end downward,

- serving as a wedge, and I will refer to it as a "wedge-piece." Two portions of its periphery are parts of a frustum of a cone. Two other considerable surfaces opposite to each other are flattened, as indicated by *m m*. A substantial tube *I*, of soft vulcanized rubber, is fitted on this wedge-piece. I have in my experiments used such material with fabric therein—a short length of thick rubber hose.
- 10 The upper end of this rubber tube projects considerably above the nut *D'*, while its lower end matches upon and is distended as required by the forcible raising of the tapering wedge-piece *M* within it.
- 15 *H* is a block of wood or other suitable material loosely inclosing the tube *D*. Its upper end is properly formed to engage in the rabbet *b'* and make a tight joint there. Its lower end forms a fair surface to press strongly against the upper edge of the rubber tube *I*. A rabbet *h*, formed on this lower end, contributes to prevent any lateral displacement.
- 20 The rubber *I* should be of such width as to extend above the tapering plug *M* and the nut *D'* sufficiently to allow considerable movements of these parts up and down relatively to each other.
- 25 When the parts are slackened, they may be applied by introducing the rod *D* and its attachments within the pipe *A*; but they should be so proportioned that there will not be much room to spare. When all are in position, the thumb-nut *F* is turned, drawing upward the tube *D*, and consequently the wedge-piece *M*, and distending the lower end of the rubber. The flat sides *m m* allow the tube to draw into a corresponding flat form at each side against those surfaces, and there is no tight contact between the rubber and the inner surfaces
- 30 of the pipe *A* against those points; but the rounded parts of the wedge-piece bear firmly and forcibly against the rubber which is between them and the adjacent portions of the interior of the pipe and it wedges fast. My
- 35 experiments indicate that the testing pressure may be much in excess of the six hundred pounds per square inch ordinarily required, and the force will be effectually resisted by the wedging contact thus induced in the interior of the pipe. If the wedge-piece were cylindrical, it would distend equally all around, and the invention may be used with some success in such form; but it is important to let the compressed air flow upward and fill the
- 40 whole space in the pipe and hub clear to the top, as there may be imperfections in the casting in the upper part which would not be discovered except by the extension of the test to the end of each.
- 45 The individual plug which is selected to receive the connection for the testing apparatus, the pump, gage, &c., (not shown,) is attached by screwing upon the upper end of the small pipe *D* thereof. A tight joint may
- 50 be made in any ordinary manner, as by smearing with red lead at each use. The other testing-plugs in this set which do not receive the

testing apparatus and are simply required to maintain the tightness of the joint each have the upper end of the tube *D* closed by a cap *D'*.

It will be understood that although I have called the nut a "thumb-nut" it is stout and may receive a lever for turning it with great force to insure tightness of the fit. Such lever may be also important in releasing the nut when it has been screwed up with great force to insure a tight joint.

To complete the liberation of the plug, the nut is unscrewed to a considerable distance—say an inch or more—and then a blow of the hand with or without the interposition of something, as a piece of board, sends the rod *D* and the attached wedge-piece *M* downward sufficiently and the rubber tube *I* contracts again and the parts may be lifted with perfect ease.

Modifications may be made without departing from the principle or sacrificing the advantages of the invention.

Additions may be made. Instead of the thumb-nut shown there may be other devices, as a hand-wheel, adapted to allow the easy application of more force. The soft-rubber washer *G* under the iron washer *E* is mainly useful in insuring an air-tight joint around the pipe *D*. If the rubber *C* below the disk *B* is sufficiently thick and close-fitting, this rubber *G* above may be omitted.

In the modification shown in Fig. 5 holes *m*# are bored through the wedge-piece *M*# and holes *h*# are produced in the block *H*#, which allow the compressed air to flow through and fill and test the pipe quite to the end without requiring that the wedge-piece have the flat places *m*, which are in the form first described. There are liable to be blow-holes in the casting, and it is important to test not only the main parts of the several pipes in the building, but also the ends of the several branches. To do this the compressed air must be allowed to flow past the wedge-piece. In the form shown in Figs. 1, 2, 3, and 4 the compressed air flows along the flat places at the sides; but that form of the wedge-piece concentrates the strong distending action at two points in the interior of the pipe. It is better to allow the wedge-piece to be made without the flat places—a complete truncated cone. The apertures shown in the wedge-piece and in the block in Fig. 5 allow of this. It may be understood that in this modification the wedge-piece distends the elastic rubber tube equally in all directions, so that the strain on the interior of the pipe is equal all around. This construction is preferable with large and thin pipes; but with ordinary pipes the flat-sided wedge-piece is preferable.

I claim as my invention—

1. A testing-plug comprising a disk *B* having a soft face *C* and a hole *b*, in combination with a screw-threaded tube *D* and a nut *F* matching thereon, and with a wedge-piece *M* adapted to be introduced and apply loosely

within a pipe end, and frictional material I adapted to be strongly distended by the wedge-piece, all arranged to serve substantially as herein specified.

5. 2. A testing-plug comprising a disk B having a soft face C and a hole *b*, in combination with a screw-threaded tube D and a nut F matching thereon, and with a wedge-piece M adapted to apply loosely within a pipe end, and flexible material I in tubular form embracing such wedge-piece, and means as the nuts D' and D² for allowing the wedge-piece to be shifted axially in either direction by force applied to the tube D and having provisions *m* for allowing compressed air to pass the wedge-piece, all substantially as herein specified.

15. 3. A testing-plug comprising a disk B having a soft face *c* and hole *b*, in combination with a screw-threaded tube D and a nut F

matching thereon, and with a wedge-piece M adapted to apply loosely within a pipe end 20 A A', and flexible material I in tubular form embracing such wedge-piece, and means as nuts D' and D² for allowing the wedge-piece to be shifted axially in either direction by force applied to the tube D and having provisions 25 *m* for allowing compressed air to pass the wedge-piece, all substantially as herein specified.

In testimony that I claim the invention above set forth I affix my signature in presence of two witnesses.

THOMAS G. CLIFFORD.
